United States Patent Office

Des. 188,390
Patented July 12, 1960

188,390

FLATIRON HOLDER

Lucille L. Bold, 3204 Birkshire Way, Sacramento, Calif.

Filed May 11, 1959, Ser. No. 55,859

Term of patent 7 years

(Cl. D49—6)

Fig. 1

I claim the ornamental design for a flatiron holder, as shown.
